COMBINED RECORDER AND REPRODUCER

Rudolph F. Mallina, Little Neck, N. Y., assignor
to Bell Telephone Laboratories, Incorporated,
New York, N. Y., a corporation of New York

Application February 15, 1933, Serial No. 656,832

11 Claims. (Cl. 179—100.1)

This invention relates to sound recorders and reproducers and particularly to combinations of fundamentally different types of sound storing devices, such as the disc and magnetized tape type.

In making a high quality disc record, such as is used for sound pictures, it is customary to record the sound on several machines, one of the records so produced being carefully preserved while the others are played back to test the fitness of the record for production purposes. The records played back are destroyed by the reproducing stylus and hence cannot be used for processing. To make these play-back records, however, the same apparatus is used as for the record to be processed and this duplication of apparatus naturally increases the expense of producing a good sound record.

The object of this invention is to provide an economical means for testing the quality of a record before it is processed without injuring the record by the testing.

In its preferred form this invention comprises a high quality recorder of the disc type adapted to make a record which may be processed to form a more permanent record combined with a recorder of the telephone type which furnishes the record testing means. Duplication of apparatus is avoided by using a single housing, a common microphone, amplifying system receiver and driving mechanism. Novel means herein-after to be described for making either of the recorders effective exclusively are also provided. The sound may be recorded simultaneously on both the disc and tape and then played back from the tape as often as necessary to ascertain the character of the recorded matter after which the disc record if found satisfactory may be processed into a more permanent form. If desired, the records can be made on the telephone first, played back and subsequently re-recorded on the disc and processed.

A simple form which this invention may take is illustrated in the accompanying drawings in which:

Fig. 1 is a plan view of the combined recorder with the disc cut away to expose the telephone apparatus;

Fig. 2 is the corresponding elevational view in section; and

Fig. 3 is a wiring diagram of the electrical apparatus included in the combined recorder.

The disc recorder is comprised of a heavy turntable 10 driven through a friction clutch 11, vibration

absorbing means 13, reduction gear 14 and motor 15, the latter comprising the source of motive power for both recorders. In addition to the vibration absorbing means 13, the motor 15 is supported by two spiral springs 16 and 17, the former being vertical and positioned over the center of gravity of the supported mass and the latter being horizontal and formed into a four-sided loop, each side being secured to a corresponding hook 18 of platform 19 to which the motor 15 is bolted. This motor suspension is described at length in my copending application, Serial No. 559,843, filed August 28, 1931 and the vibration absorbing means 13 is shown in detail in my copending application Serial No. 491,844, filed October 29, 1930.

A disc record 20 is shown in place on the turntable 10 and in operative relation thereto are shown a recorder 21 and a reproducer 22, each pivotally mounted for vertical movement on their respective supporting arms 23 and 24 which in turn are adapted to move horizontally by means of pivots 25 and 26, respectively.

The drive for the disc recorder may be any suitable feed mechanism and the one selected for purposes of illustration comprises a resilient arm 27 rigidly secured to the recorder arm 23 through the pivot member 25 and driven laterally by the action of a spiral groove 28 on the bristles of a brush 29 which is secured to the free end of resilient arm 27. The spiral groove is engraved on the underside of the turntable 10 and as the turntable is rotated, the walls of the groove contact with the brush to move it laterally at a rate determined by the pitch of the groove. Through the rigid connection to the recorder arm, the recorder is made to cut a similarly pitched groove in the record blank.

This, with the exception of the appropriate switches and electrical controls, comprises the mechanical portion of the disc recorder. The telephone apparatus comprises essentially polarizing magnet P, translating magnet T, a metal tape 30 and reels 31 and 32. The reels are driven from the spindle 12 through pulley 33, a suitable rope drive 34 and the direction changing pulleys 35 and 36. The tape 30 is passed over guide pulleys that are concentric with the drive pulley and the direction changing pulleys, but are free to rotate with respect thereto.

To effect the object of this invention, means must be provided for engaging the telephone drive with or disengaging it from the turntable drive. In the example shown, all of the means used for this purpose comprise cone clutches 37

which are operable by a vertical motion of their respective supporting means. The main driving pulley 33 is free to move vertically on spindle 12 and is supported by freely rotating guide pulley 37 which in turn rests upon a spider member 38, the arms of which ride upon cam surfaces 39. These cam surfaces are merely inclined planes. The spider member 38 is secured to an arm 40 at the end of which is secured a control knob 10 41 moving in a slot 50. Rotating the spider counter-clockwise raises pulley 33 and causes it to engage the lower portion of cone clutch 11 by which it is driven, and thereby initiates the operation of the telephonic phonograph. Rotating the spider clockwise lowers the pulley 33 and disengages the telephonic apparatus from the disc phonograph apparatus. Suitable spring means (not shown) may be interposed between the clutch 11 and pulley 33 to insure a positive 20 releasing action.

When it is desired to record or reproduce, reel 32 becomes a driving reel and is positively driven from the rope drive 34 by lowering clutch 43 until the reel is contacted. This causes the reel 25 to rotate in the same direction as spindle 12 and to pull the tape first through the polarizing magnet P and then through the translating magnet T. It is necessary, of course, that reel 31 be disengaged from the driving means when reel 30 32 is so engaged, and to insure this condition, a lever 44 fulcrumed at 45 is supplied, the reel clutches being operated by the lever from opposite sides of the fulcrum. The lever 44 is operated by plunger 46. When the plunger is in 35 its lowest position, the condition just described obtains.

When it is desired to rewind, reel 31 is made the driving reel and it is accordingly driven positively by raising plunger 46 which through 40 lever 44 engages clutch 47 with reel 31 and disengages clutch 43. The rope drive 34 is thus made effective to drive the rewind reel 31.

A protective cover 48 may be supplied for the telephonic apparatus and a larger casing 49 can be used to house the entire machine. The 45 turntable 10 is removable and may be placed vertically in the casing 49 if the machine is to be portable. This, however, is not a part of the invention and the housing may take any 50 other form which may seem more desirable.

This completes the description of the more important mechanical features of the machine.

The electrical connections to the machine and exterior apparatus are shown in the diagram of 55 Fig. 3. It is understood, of course, that numerous switching arrangements are possible and that the diagram shown is merely illustrative of the preferred arrangement.

In detail, 60 is a microphone, preferably of 60 the electromagnetic type, which is used to pick up the sound to be recorded. The sound controlled electrical currents so generated are strengthened in amplifier 61 and are then recorded either on the tape 30 by means of translating 65 magnets T or on the blank disc 20 by means of the disc recorder 21. After the currents are recorded, they may be reproduced from either of the records, strengthened again in amplifier 61 and converted into sound in the receiver 62. The 70 switches are shown operated as follows:

To record, switch 63 is thrown upward thereby completing the circuit from the microphone 60 through the amplifier 61 and transformer 64 to switches 65 and 66. For tape recording, switch 75 66 remains opened and switch 65 is closed, thus

sending the current through the coils 67 of the translating magnets T. For disc recording, switch 65 is opened and switch 66 is closed through its upper contacts to send the current through the disc recorder 21. For combined tape and disc 5 recording, switch 65 is closed in addition to the last mentioned arrangement.

To reproduce on the telephone, switch 65 is closed, switch 63 is closed through its lower contacts, switch 66 is opened and switch 70 is closed through the receiver contacts. This completes a circuit from coil 67 through amplifier 61 to the receiver 62. Reproduction from the disc record is accomplished by closing switches 63 and 66 through the lower contacts of each, 15 closing switch 70 again through its receiver contacts and opening switch 65. This substitutes reproducer 22 for the coils 67 of the telephone.

To re-record from the tape to the disc, switch 65 is closed, switch 63 is closed through its lower 20 contacts, switch 66 is opened and switch 70 is closed through the disc recorder contacts. This substitutes the disc recorder 21 for the receiver 62 in the telephone reproducing arrangement. Coils 68 are used for depolarizing and coils 69 25 for polarizing the magnetic tape 30 before it is used, in accordance with known practice as illustrated in detail in a copending application of C. N. Hickman et al., Serial No. 530,168, filed April 15, 1931, now Patent No. 2,003,968, June 4, 1935, 30 or in the somewhat similar manner taught by S. M. Baruch in U. S. Patent No. 1,774,821, September 2, 1930.

To operate the machine the motor 15 is started. This rotates turntable 10 and it will be noted 35 that the turntable rotates as long as the motor is running irrespective of which recorder is used, its rotating mass supplying a very useful fly-wheel action to either driving system. With the turntable rotating, the disc recording and re- 40 producing functions may be carried out, preceded, of course, by the appropriate switching operations as outlined above. For example, to record on disc, knob 41 is turned clockwise to its limiting position in slot 50 to disengage the telephone driving apparatus from the main drive. The recorder 21 is swung over to and in contact with the edge of a record blank which was placed upon the turntable before the turntable was rotated and feed brush 29 is made 50 to engage groove 28 to initiate the lateral feed motion of the recorder 21. At the end of the recording, the recorder is raised and returned to a position which is clear of the record. This action causes feed brush 59 to sweep across groove 55 28 but no damage results to either the brush or groove because the bristles of the brush possess enough flexibility and the grooves enough rigidity to resist permanent deformation.

Reproduction from a disc record requires no 60 additional mechanical manipulations and the machine may be used as any ordinary reproducing phonograph.

To record on or reproduce from the metallic tape, knob 41 is moved to its other limiting 65 position in slot 50 to connect the telephone apparatus to the driving mechanism. This, however, does not affect any of the disc recording and reproducing functions and the latter may be carried on simultaneously with the telegraph 70 phonic functions. To record or reproduce, plunger 46 is depressed and to rewind the plunger is raised. These operations are also to be preceded by the appropriate switching operations. In the arrangement shown, the rewind operation 75

is necessary before each reproduction since but one tape is used.

This combined recorder can be used in any sound studio where recording is done on soft discs which are to be processed into a more permanent form. Since the magnetic tape recorder is a high quality recorder, sounds may be recorded first on the tape, then reproduced from the tape to ascertain their character and subsequently, if found suitable, re-recorded on the disc recorder. By connecting the receiver into the re-recording circuit, it is possible to monitor the sounds being so recorded.

The uses and arrangements described above by no means exhaust the possibility of this invention and its scope therefore is not to be limited thereby but by the appended claims.

What is claimed is:

1. Means for ascertaining the character of sound recorded in a delicate medium comprising a plurality of media including a delicate medium and a rugged medium, means for impressing both types of media with the same sound, and means for reproducing the sound from the rugged medium.

2. Disc recording and reproducing apparatus, telephonic recording and reproducing apparatus, unitary driving means, and selective means for associating the driving means with one or both types of said recording and reproducing apparatus.

3. In a driving means for telephonic recording and reproducing apparatus, a flywheel, means on the flywheel for supporting and driving a grooveless disc record blank, a disc recorder, and means also on said flywheel cooperating with the disc recorder to feed the recorder across the record blank.

4. Disc and telephonic recording and reproducing apparatus, unitary driving means, and means comprising a cone clutch for engaging the telephonic recording and reproducing apparatus with the driving means.

5. Disc phonograph apparatus comprising a recorder and a reproducer, telephonic apparatus comprising translating magnets polarizing and depolarizing magnets and associated energizing means, a common source of sound controlled electrical currents, a common amplifier, a common receiver, and switching means for effecting various combinations of said apparatus

tus including a combined disc and telephonic recorder, and a telephonic reproducer.

6. In combination, electromechanical sound translating device and a disc record blank cooperating therewith, an electromagnetic translating device and a magnetizable body cooperating therewith, a common driving means for the record blank and magnetizable body comprising a source of power, a drive shaft, vibration absorbing means intermediate the drive shaft and source of power, a flywheel for still further absorbing vibrations, said flywheel being adapted to receive and rotate the record blank and to cooperate with the electromechanical sound translating device to feed the latter evenly across the blank, reels for the magnetizable body, and selective starting means for the reels.

7. Disc recording apparatus including a recording stylus, telephonic reproducing apparatus, a common driving means, a common amplifier and switching means for operatively connecting together the disc recording apparatus, amplifier and telephonic reproducing apparatus whereby sound controlled electrical currents represented in the telephonic apparatus as variations in the magnetization of a body are regenerated and made to vibrate a recording stylus.

8. Apparatus, driving and switching means as claim 7, and means for monitoring the regenerated sound controlled electrical currents.

9. Telephonic recording and reproducing apparatus, driving means therefor including a flywheel, a grooveless disc record blank, a recorder cooperating therewith and means on the flywheel cooperating with the disc recorder to drive the recorder across the record blank.

10. Disc recording and reproducing apparatus, telephonic recording and reproducing apparatus, unitary driving means and selective means for associating the driving means with either type of said recording and reproducing apparatus.

11. Disc phonograph apparatus including a recorder, telephonic apparatus comprising translating magnets and energizing means therefor, a common source of sound controlled electrical currents, a common amplifier and switching means for effecting various combinations of said apparatus including a combined disc and telephonic recorder.

RUDOLPH F. MALLINA.
